TYPEWRITER

Harry Bates, New York, N. Y., assignor to Bates Laboratories, Inc., New York, N. Y., a corporation of New York

Application January 11, 1934, Serial No. 706,245

6 Claims. (Cl. 197—57)

This invention relates to typewriters in general.

Among the objects of the present invention it is aimed to provide a writing machine or typewriter equipped with a plate or board provided with a plurality of character defining areas corresponding to the universal four row keyboard with the figures arranged in the upper row and the letters arranged in the three lower rows, in combination with a type carrier and a key operatively connected to said carrier and movable to register with the character defining area in said plate corresponding to the type desired to be selected constituting a practical typewriter suitable for use as an educational machine for children and also suitable for use by the uninitiated so-called one finger operators, which machine can be produced at such low cost that it can be used to good advantage as a feeder for the more expensive standard typewriters. The word "feeder" in this instance connotes the type of machine used to interest prospective purchasers in a more expensive machine.

It is still a further object of the present invention to provide an improved typewriter having a type carrier, a chart having a plurality of character defining areas, and a selector cooperating with said chart and said type carrier so that registration of a character defining area by said selector will in turn position in printing position a type on said type carrier corresponding to such character defining area.

It is still another object of the present invention to provide an improved one finger operated typewriter having a flexible band with type formations thereon, a rotatable support for said band, a universal keyboard having a plurality of character defining areas corresponding to the type on said band, and a selector key operatively connected to said support and movable to register with said character defining areas according to the type to be selected in turn to position a type on said flexible band corresponding to the character defining area in registration with said selector.

These and other features, capabilities and advantages of the invention will appear from the subjoined detail description of one specific embodiment thereof illustrated in the accompanying drawings in which

Figure 1 is a plan with parts broken away;

Fig. 2 is a section on the line 2—2 of Fig. 1;

Fig. 3 is a fragmental section on the line 3—3

55 of Fig. 1;

Fig. 4 is a fragmental section on the line 4—4 of Fig. 1;

Fig. 5 is a fragmental detail on the line 5—5 of Fig. 4; and

Fig. 6 is a fragmental detail showing the escape-
ment for the platen.

In the embodiment shown, there is provided a main frame 1 having two side walls 2, 3, a front wall 4 and a rear wall 5. To the side walls 2 and 3 by means of the lugs 6, there is secured the base 10 plate 7 preferably inclining upwardly from a point spaced from the front wall 4 to a point spaced from the rear wall 5.

On the base plate 7, there is pivotally mounted as a unit the keyboard 8, and platen 9 so that 15 they may rock together into impression producing position in regard to the type 10 and 11 on the type carrier 12 mounted on the segmental frame 13 secured to the cylinder 14 pivotally mounted on the post 15 extending upwardly from 20 the base plate 7.

Extending upwardly from the sides of the base plate 7 near its rear edge are provided the ears 16 for receiving the shaft 17 on which the casting 18 is rotatably mounted. The casting 18 is fixed 25 to the rear ends of the arms 19 and 20 which extend forwardly and at their front ends are connected to the keyboard 8. The keyboard 8 preferably consists of a plate having a plurality of 30 character designating areas corresponding in notation to the notations of the keys of the universal keyboard of a typewriter.

The platen 9 is preferably journaled at its ends in the bearings 21 and 22 extending upwardly 35 from the ends of the carriage forming plate 23, the lower edge of which is slidably mounted in the guideway formed between the pairs of short lugs 24, the pairs of long lugs 25 adjacent the ends of the casting 18 and the upwardly extending arms 26 and 27 disposed approximately at the middle 40 of the casting 18.

For resiliently anchoring the platen against rotation during printing, there is fixed to the platen at one end thereof inside the bearing 22 the toothed wheel 28 engaged by the spring detent 29 extending up from the plate 23. For line spacing the platen 9 the ends of the platen have fixed thereto the knurled knobs 30 and 31. Any suitable additional line spacing mechanism can of course be added if desired without interfering 50 with the operation of this machine.

The platen 9 can be equipped with any suitable paper guide, such as the guide plate 32 extending rearwardly and upwardly from the plate 23 and also provided with any suitable paper feed mecha- 55

nism, such as rollers 33 held in frictional engagement with the platen 9 by the spring plate 35 secured to the plate 32. The rollers 33 rotate on the shaft 36 which is mounted in bearings 34 formed on the plate 35. Upwardly from the shaft 36 and in frictional engagement with the platen 9, there also extend the spring fingers 37 and 38 for further guiding the paper on the platen 9 and for aiding the rollers 33 in their line feeding 10 action of the paper.

The plate 8 is maintained in its normal raised position with its cushions 39 held against the heads 40 of the pins 41 extending upwardly from the front ends of the base 7 by the spring 42 secured to the upper face of the base 7 and engaging the lower face of the finger 43 extending forwardly from the casting 18.

The plate 8 is preferably provided with four rows of character defining areas 44 corresponding in notation and relative spacing from one another to the keys of the universal keyboard of a standard typewriter. These areas 44 are in the form of depressions, see Fig. 2, with which the key 45 here referred to as a universal key 20 is intended to register to position the type on the type carrier 12. The type 10 and 11 are arranged in pairs, each pair corresponding to one of the areas 44 and being so arranged on the type carrier 12 that the registration of the key 45 with an area 44 will position one of the 25 corresponding pair of type in printing position.

The type carrier 12 in the present instance is preferably composed of a flexible strip of thin gauge metal into which the type 10 and 11 have 30 been depressed. The frame 13 has an arcuate portion 46 around a portion of the outer periphery of which the band 12 extends being connected at its ends to the outer faces of the radially extending arms 47 and 48 of the frame 13. 35 The band 12 is spaced from the arm 46 at the printing point, at such location extending around the guide roller 49 pivotally mounted on the pin 50 extending upwardly from the plate 51. At the ends of the plate 51, there are provided the pins 52 and 53 on which the guide rollers 54 and 55 are pivotally mounted.

The plate 51 is secured to the upper end of the post 56 extending upwardly from the base plate 7. The pins 50, 52 and 53 are long enough to 50 permit the rollers 49, 54 and 55 to slide on the same when the band 12 is shifted from position for printing lower case type 10 into position for printing upper case type 11.

In order to shift the band 12 from position 55 for printing lower case type 10 into position for printing upper case type 11, the cylinder 14 is provided with a recess 57 to receive the curled ends of the bifurcated plate 58 fixed on the shaft 59 journaled in the bearings 60 and 61 extending upwardly from the base plate 7.

The ends of the shaft 59 have fixed thereon the forwardly extending shift bars 62 and 63 at the front ends of which there are formed the shift keys 64 and 65 respectively extending upwardly adjacent the rear sides of the plate 8.

The key 45 is pivotally connected to the front end of the bar 63 extending through the slot 67 formed in the cylinder 14 and adjacent its rear end bent upward at 68 and then extending upwardly through the slot 69 formed in the arm 70 of the frame 13 and ultimately terminating in the lugs 71 and 72 engaging the upper face of the arm portion 73 of the frame 13.

The arm 66 is long enough so that the key 45 78 may be moved to register with any of the areas

46 in the plate 8 and due to the pivotal mounting of the cylinder 14 on the pin 15 will cause the frame 13 to turn into proper position. The arm 66 as shown is slidably mounted in the slots 61 and 63 so that the key 45 can engage an area 5 44 in the upper row nearest the cylinder 14 and also at another time an area 44 in the lowermost row nearest the wall 4 farthest away from the cylinder 14.

For effecting an impression of the type 10 or 10 11 on the paper supported on the platen 9 after the key 45 has positioned the type selected by registering with a corresponding area 44, it will only be necessary for the operator to depress the key 45 while in engagement with such area 44 15 thereby to rock the plate about its shaft 17 until the platen 9 causes the paper supported thereon to be brought into printing engagement with the type 10, 11.

Any suitable inking arrangement may be provided. In the present instance, an inking ribbon 73 is provided and mounted to be positioned between the paper and the type so that the depression of the plate 8 will cause the ribbon 73 to be impinged between the paper on the platen 9 and the type 10 or 11. The spring 42 upon release of the key 45 will in turn return the platen 9 and plate 8 to normal non-printing position.

For letter spacing the type any suitable escapement may be provided. In the present instance, the carriage forming plate 23 has formed thereon a rearwardly extending flange 74 on the rear edge of which there are formed ratchet teeth 75 to be engaged by the upper end of the pawl 76 of the bell crank lever 77 pivotally connected to the ear 78 extending upwardly from the base plate 7. The arm 80 of the lever 77 has its free end disposed under the stop lug 81 formed at the upper end of the finger 82 extending upwardly from the base plate 7. The arm 40 26 of the casting 18 has a roller 83 mounted thereon to engage the upper face of the arm 80. The upwardly extending arm 84 of the lever 77 is connected by the spring 85 with the abutment 86 on the casting 18. 45

From the foregoing, it will thus be seen that when the plate 8 is depressed to actuate the carriage 23 into printing position, it will rock the roller 83 of the arm 26 out of engagement with the arm 80 of the lever 77 to permit the 50 spring 85 to rock the lever 77 about its pivotal point so that the toothed end of the arm 84 will be in position upon the release of the plate 8 to engage the succeeding tooth 75 on the flange 74 and thereupon when the platen 9 and carriage 55 23 move into non-printing position, the roller 83 will engage the upper edge of the arm 80 to rock the lever 77 when the carriage 23 and platen 9 will be advanced a letter space.

For advancing the platen 9 and carriage 23 60 a blank letter space, this same mechanism is operated by the depression of the plate 8 except that the type carrier 12 will be positioned so that a blank space on the same, to wit the blank space 87, will register at the printing location. The 65 band 12 in the present instance is provided with four such blank spaces corresponding with the areas 88 on the extension 89 which are so positioned relative to the blank spaces 87 on the band 12 that when they are engaged by the key 70 45 they will locate a blank space 87 on the band 12 at the printing position on the roller 49.

The ribbon 73 in the present instance extends from the supply reel 90 to the take-up reel 91. The supply reel is rotatably mounted on the up- 75

per end of the post 92 extending upwardly from the base plate 1. The take-up reel 91 is secured to the post 93 rotatably mounted between the upper end of the bracket 94 and the base plate 1.

5 The post 93 has fixed thereon the toothed wheel 95 which is engaged by the holding pawl 96 extending from the bracket 94 and also adapted to be engaged by the pawl 97 extending from the casting 18. The pawl 97 is so positioned relative 10 to the toothed wheel 95 that upon the release of the plate 8 after effecting an impression, the pawl 97 will engage the toothed wheel 95 to advance it one tooth space and therewith the feed of the ribbon 13 one tooth space.

15 From the foregoing, it will be obvious that it would be a comparatively simple matter to change over a machine made according to the present invention for a language having different characters. In order to change over a machine 20 initially equipped for use with the characters of the English language into a machine for use with the characters of the Arabic language, as an instance, it would only be necessary to remove the type carrying band 12 having characters of 25 the English language impressed thereon and substitute for it a type carrying band having characters of the Arabic language thereon and in turn either to place a second plate over the plate 8 having characters of the Arabic language marked 30 thereon or else to remove the plate 8 and its side bars 19 and 20 and substitute therefor a new plate with its side bars similar to the side bars 19 and 20 in which the new plate has formed 35 thereon characters of the Arabic language, in which case it may of course be necessary to substitute letters for some of the punctuation marks or the like. In a similar manner, a machine initially equipped to print characters of the English 40 language can also be converted into a coding or decoding machine or a machine for use by the blind. It is of course also obvious that this machine can be initially equipped to print characters of a foreign language or characters usable with a code and the like without departing from the 45 general spirit of the invention.

It is obvious that various changes and modifications may be made to the details of construction without departing from the general spirit of the invention as set forth in the appended 50 claims.

I claim:

1. The combination with a main frame, of a secondary frame pivotally connected on a horizontal axis to said main frame, a plate constituting 55 a keyboard having a plurality of character designating areas corresponding in number and position to the keys of a universal keyboard at one end of said secondary frame, a paper support carried by the other end of said secondary frame to move therewith, means for actuating said paper support to register successive areas at a common printing area, a shaft mounted to extend upwardly from said main frame, a sleeve rotatably mounted on said shaft, an arcuate bracket 60 extending laterally from said sleeve and having an arcuate surface substantially concentric with the axis of rotation of said sleeve, a bracket secured to said main frame and having a pin extending upwardly therefrom, a roller of shorter radius than the radius of said arcuate surface disposed between said arcuate surface and said paper support and rotatably mounted on said pin, a flexible band having type formed 65 thereon corresponding to the character designating areas on said keyboard and secured at its

ends to said arcuate bracket to extend around said arcuate surface and said roller, the type of said band being movable into and out of a common printing position on that portion of the periphery of said roller nearest to said paper support in accordance with the motion of said arcuate bracket, and a type selector connected to said sleeve to oscillate with said sleeve about said shaft and to oscillate independently of said sleeve about a horizontal axis, said selector being guided 10 by said keyboard to actuate said sleeve and arcuate bracket and thereby select the type desired, the actuation of said selector about its horizontal axis in a downward direction effecting the actuation of said keyboard and thereby the actuation 15 of said paper support into engagement with the type selected and positioned on said roller in said common printing area to form an impression of the type so positioned.

2. In a typewriter, a main frame, a secondary frame pivotally mounted transversely of the main frame and having a platen carried by one end thereof to move therewith and a plate constituting a keyboard carried by the other end thereof, said keyboard having character indicia arranged 25 thereon corresponding in number and position to the keys of a universal keyboard, a shaft extending upwardly from the main frame intermediate the ends of the secondary frame, a sleeve rotatably mounted on said shaft and extending thereabove, the portion of the sleeve above the shaft being diametrically slotted, a type positioning segment fixed to the upper end of said sleeve and having an arcuate face concentric with the shaft and confronting said platen, a bracket secured 30 to said main frame and having a pin extending upwardly therefrom, a roller of materially shorter radius than the radius of said arcuate face disposed in engagement with said arcuate face and between said arcuate face and said platen and 35 rotatably mounted on said pin, a flexible band having type formed thereon corresponding to the character designating areas on said keyboard and secured at its ends to the ends of said arcuate face and extending from one end to the other 40 partly around said arcuate face and partly around said roller, the type on said flexible band being movable into and out of a common printing position on that portion of the periphery of said roller nearest to said paper support in accordance 45 with the motion of the type positioning segment to present a selected type in opposition to said platen, and an actuating member mounted in said slot for oscillation with said sleeve about the axis of the shaft and for oscillation independent of said sleeve about a horizontal axis and having a type selector on its forward end movable toward and from said shaft for positioning over a selected unit of the type indicia to engage and depress the keyboard and thereby tilt 50 the secondary frame and urge the platen toward the selected type.

3. The combination with a main frame, of a secondary frame pivotally connected on a horizontal axis to said main frame, a plate constituting 65 a keyboard having a plurality of character designating areas corresponding in number and position to the keys of a universal keyboard at one end of said secondary frame, a paper support carried by the other end of said secondary frame to move therewith, means for actuating said paper support to register successive areas at a common printing area, a shaft mounted to extend upwardly from said main frame, a sleeve rotatably mounted on said shaft, an arcuate 70

bracket extending laterally from said sleeve and having an arcuate surface substantially concentric with the axis of rotation of said sleeve, a bracket secured to said main frame and having a pin extending upwardly therefrom, a roller of shorter radius than the radius of said arcuate surface disposed between said arcuate surface and said paper support and rotatably mounted on said pin, a flexible band having type formed thereon corresponding to the character designating areas on said keyboard and secured at its ends to said arcuate bracket to extend around said arcuate surface and said roller, the type of said band being movable into and out of a common printing position on that portion of the periphery of said roller nearest to said paper support in accordance with the motion of said arcuate bracket, said arcuate bracket having a recess in its arcuate face to receive said band and roller to guide the same against displacement, and a type selector connected to said sleeve to oscillate with said sleeve about said shaft and to oscillate independently of said sleeve about a horizontal axis, said selector being guided by said keyboard to actuate said sleeve and arcuate bracket and thereby select the type desired, the actuation of said selector about its horizontal axis in a downward direction effecting the actuation of said keyboard and thereby the actuation of said paper support into engagement with the type selected and positioned on said roller in said common printing area to form an impression of the type so positioned.

4. In a typewriter, a main frame, a secondary frame pivotally mounted transversely of the main frame and having a platen carried by one end thereof to move therewith and a plate constituting a keyboard carried by the other end thereof, said keyboard having character indicia arranged thereon corresponding in number and position to the keys of a universal keyboard, a shaft extending upwardly from the main frame intermediate the ends of the secondary frame, a sleeve rotatably mounted on said shaft and extending thereabove, the portion of the sleeve above the shaft being diametrically slotted, a type positioning segment fixed to the upper end of said sleeve and having an arcuate face concentric with the shaft and confronting said platen, a bracket secured to said main frame and having a pin extending upwardly therefrom, a roller of materially shorter radius than the radius of said arcuate face disposed in engagement with said arcuate face and between said arcuate face and said platen and rotatably mounted on said pin, a flexible band having type formed thereon corresponding to the character designating areas on said keyboard and secured at its ends to the ends of said arcuate face and extending from one end to the other partly around said arcuate face and partly around said roller, the type on said flexible band being movable into and out of a common printing position on that portion of the periphery of said roller nearest to said paper support in accordance with the motion of the type positioning segment to present a selected type in opposition to said platen, said type positioning segment having a recess in its arcuate face to receive said band and roller to guide the same against displacement, and an actuating member mounted in said slot for oscillation with said sleeve about the axis of the shaft and for oscillation independent of said sleeve about a horizontal axis and having a type selector on its forward end movable toward and from said shaft

for positioning over a selected unit of the type indicia to engage and depress the keyboard and thereby tilt the secondary frame and urge the platen toward the selected type.

5. The combination with a main frame of a secondary frame pivotally connected on a horizontal axis to said main frame, a plate constituting a keyboard having a plurality of character designating areas corresponding in number and position to the keys of a universal keyboard at one end of said secondary frame, a paper support carried by the other end of said secondary frame to move therewith, means for actuating said paper support to register successive areas at a common printing area, a shaft mounted to extend upwardly from said main frame, a sleeve rotatably mounted on said shaft, an arcuate bracket extending laterally from said sleeve and having an arcuate surface substantially concentric with the axis of rotation of said sleeve, a bracket secured to said main frame and having a pin extending upwardly therefrom, a roller of shorter radius than the radius of said arcuate surface disposed between said arcuate surface and said paper support and slidably and rotatably mounted on said pin, a flexible band having type formed thereon corresponding to the character designating areas on said keyboard and secured at its ends to said arcuate bracket to extend around said arcuate surface and said roller, the type of said band being movable into and out of a common printing position on that portion of the periphery of said roller nearest to said paper support in accordance with the motion of said arcuate bracket, said arcuate bracket having a recess in its arcuate face to receive said band and roller to guide the same against displacement, a type selector connected to said sleeve to oscillate with said sleeve about said shaft and to oscillate independently of said sleeve about a horizontal axis, said selector being guided by said keyboard to actuate said sleeve and arcuate bracket and thereby select the type desired, the actuation of said selector about its horizontal axis in a downward direction effecting the actuation of said keyboard and thereby the actuation of said paper support into engagement with the type selected and positioned on said roller in said common printing area to form an impression of the type so positioned, said band having two rows of type thereon, and means to vertically shift said sleeve to position the band according to the row of type in which a type is selected.

6. In a typewriter, a main frame, a secondary frame pivotally mounted transversely of the main frame and having a platen carried by one end thereof to move therewith and a plate constituting a keyboard carried by the other end thereof, said keyboard having character indicia arranged thereon corresponding in number and position to the keys of a universal keyboard, a shaft extending upwardly from the main frame intermediate the ends of the secondary frame, a sleeve rotatably mounted on said shaft and extending thereabove, the portion of the sleeve above the shaft being diametrically slotted, a type positioning segment fixed to the upper end of said sleeve and having an arcuate face concentric with the shaft and confronting said platen, a bracket secured to said main frame and having a pin extending upwardly therefrom, a roller of materially shorter radius than the radius of said arcuate face disposed in engagement with said arcuate face and between said arcuate face and said platen and slidably and rotatably mounted on said pin, a flexible band having type formed thereon corresponding to the character designating areas on said keyboard and secured at its ends to the ends of said arcuate face and extending from one end to the other partly around said arcuate face and partly around said roller, the type on said flexible band being movable into and out of a common printing position on that portion of the periphery of said roller nearest to said paper support in accordance with the motion of the type positioning segment to present a selected type in opposition to said platen, said type positioning segment having a recess in its arcuate face to receive said band and roller to guide the same against displacement, and an actuating member mounted in said slot for oscillation with said sleeve about the axis of the shaft and for oscillation independent of said sleeve about a horizontal axis and having a type selector on its forward end movable toward and from said shaft

ably mounted on said pin, a flexible band having type formed thereon corresponding to the character designating areas on said keyboard and secured at its ends to the ends of said arcuate 5 face and extending from one end to the other partly around said arcuate face and partly around said roller, the type on said flexible band being movable into and out of a common printing position on that portion of the periphery 10 of said roller nearest to said paper support in accordance with the motion of the type positioning segment to present a selected type in opposition to said platen, said arcuate bracket having a recess in its arcuate face to receive said band 15 and roller to guide the same against displacement, an actuating member mounted in said slot

for oscillation with said sleeve about the axis of the shaft and for oscillation independent of said sleeve about a horizontal axis and having a type selector on its forward end movable toward and from said shaft for positioning over a selected 5 unit of the type indicia to engage and depress the keyboard and thereby tilt the secondary frame and urge the platen toward the selected type, said band having two longitudinally extending parallel rows of type thereon, and means to vertically shift said sleeve and thereby said roller to position the band according to the row of type in which a type is selected without affecting the position of said bracket. 10

HARRY BATES. 15
